(57) **CLAIM**

The ornamental design for a jump training toy, as shown and described.

DESCRIPTION

FIG. 1 is a front perspective view of the jump training toy showing my new design;

FIG. 2 is a left side view thereof;

FIG. 3 is a right side view thereof;

FIG. 4 is a top view thereof;

FIG. 5 is a bottom view thereof;

FIG. 6 is a front view thereof;

FIG. 7 is a back view thereof;

FIG. 8 is a front perspective view showing the design with its components in a separated state; and,

FIG. 9 is a front perspective view showing the design with its components in a storage configuration.

The broken lines shown in FIGS. 1-4, 8 and 9 are included for the purpose of illustrating features of the jump training toy that form no part of the claimed design.

1 Claim, 7 Drawing Sheets

FIG. 2

FIG. 3

FIG. 6

FIG. 7

FIG. 8

FIG. 9
